(57) CLAIM

The ornamental design for a handbag, as shown and described.

DESCRIPTION

FIG. 1 is a bottom plan view of a handbag showing my new design;

FIG. 2 is a left side elevation view thereof;

FIG. 3 is a front elevation view thereof;

FIG. 4 is a right side elevation view thereof; and,

FIG. 5 is a top plan view thereof.

The broken line showing of strap support rings, in FIGS. 2, 3, and 5, is for illustrative purposes only and forms no part of the claimed design.
